UNITED STATES PATENT OFFICE

168,495

ARTIFICIAL FLOWER BUNNY

Emmanuel Benetos, Astoria, N. Y.

Application August 2, 1950, Serial No. 11,554

Term of patent 14 years

(Cl. D34—2)

To all whom it may concern:

Be it known that I, Emmanuel Benetos, a citizen of Greece, residing at Astoria, Long Island, in the county of Queens and State of New York, have invented a new, original, and ornamental Design for an Artificial Flower Bunny, of which the following is a specification, reference being had to the accompanying drawing, forming part thereof.

Fig. 1 is a back view of an artificial flower bunny, showing my new design.

Fig. 2 is a front view of said artificial flower bunny.

Fig. 3 is a side view thereof.

I claim:

The ornamental design for an artificial flower bunny, as shown.

EMMANUEL BENETOS.
